UNITED STATES PATENT OFFICE.

WILLIAM F. SCHWEIGER, OF ROCHESTER, NEW YORK, ASSIGNOR TO MULTIPROCESS COMPANY, OF ROCHESTER, NEW YORK, A CORPORATION OF NEW YORK.

STAMP-AFFIXER.

1,379,651.

Specification of Letters Patent.

Patented May 31, 1921.

Application filed September 26, 1918. Serial No. 255,732.

To all whom it may concern:

Be it known that I, WILLIAM F. SCHWEIGER, a citizen of the United States, residing at Rochester, in the county of Monroe and 5 State of New York, have invented certain new and useful Improvements in Stamp-Affixers; and I do hereby declare the following to be a full, clear, and exact description of the same, reference being had to the accompanying drawings, forming a part of 10 this specification, and to the reference-numeral marked thereon.

My invention relates to stamp affixers and has for its object to provide such a machine 15 with a printing device adapted to print on a stamp, label or other article, simultaneously with the operation of affixing the same. Another object of my invention is to provide a device for canceling a stamp simultaneously 20 with the operation of affixing the same. A still further object of my invention is to provide improved means for applying moisture to the surface upon which the stamp is affixed. To these and other ends the invention 25 consists in certain improvements and combinations of parts, all as will be hereinafter more fully described, the novel features being pointed out in the claims at the end of the specification.

Referring to the drawings:

Figure 1 is a side elevation of a stamp affixer constructed according to the principles of my invention.

Fig. 2 is a front elevation of the same.

Fig. 3 is a view similar to Fig. 1 with a part of the casing broken away to expose the parts beneath,

Fig. 4 is an enlarged central sectional view,

Fig. 5 is a view similar to Fig. 4, parts being broken away and other parts being shown in different relations,

Fig. 6 is a view similar to Fig. 5 but showing the parts in still other relations.

Fig. 7 is a section on the line 7^x—7^x of Fig. 4.

Fig. 8 is a section on the line 8^x—8^x of Fig. 5,

Fig. 9 is a section on the line 9^x—9^x of Fig. 5.

Fig. 10 is a detail sectional view through the pivots of the ink reservoir.

Fig. 11 is a bottom plan view of the printing device,

Fig. 12 is a section on the line 12^x—12^x of Fig. 11, and

Fig. 13 is a section on the line 13^x—13^x of Fig. 11.

Similar reference numerals in the several figures indicate the same parts. 60

I have shown my invention applied to a commercial form of stamp affixing machine, which comprises a frame or housing 1 mounted on a base 2, having a central aperture 3, in alignment with which is mounted a vertical reciprocating shaft or plunger 4, provided at its upper end with an operating knob or handle 5 and provided at its lower end with an affixing head 6 in which are carried one or more type blocks 7. At one side 70 of the plunger 4 is mounted a stamp receptacle 8 and guideway comprising a vertically extending guide wall 9, the lower end of which is curved laterally as at 10 to guide and discharge the stamp strip 11 into the 75 path of the affixing head of the plunger 6 as it approaches the limit of its downward movement.

The plunger 4 is rectangular in cross section and is surrounded by a carriage 12, by 80 which the stamp feeding fingers 13 are carried. The plunger is movable independently of the carriage so that the carriage may be arrested when the stamp strip has been projected the proper distance to discontinue the 85 feeding thereof, and permitting the plunger to be moved to sever and affix the stamp by devices presently to be described. The carriage is connected to the plunger to be moved thereby by means of a steel ball mounted in 90 an aperture or recess in the plunger and forced outwardly by means of an expansion coiled spring 14 interposed between the ball and the bottom of the recess. The projecting portion of the ball is adapted to coöperate with the edge of an aperture or recess 95 provided therefor in the carriage. The upper end of the carriage is offset slightly and forms a projection 16 which extends through an aperture provided therefor in 100 the top of the casing where it may be engaged by a suitable instrument to retain the carriage while the plunger is moved downwardly when it may be locked in an inoperative position by means of a locking bolt 105 17 on the carriage which is adapted to coöperate with a recess 18 in the plunger to retain it depressed with the head 6 within the recess 3 of the base.

The feeding fingers 13 comprise a plurality of thin steel bars pivoted on a rod 19 mounted in a pair of ears 20 projecting from

the carriage and adapted to engage the perforations between the successive stamps of the strip during the feeding movement. The fingers are yieldingly held in engagement 5 with the strip of stamps by means of spring fingers 21 secured by screws to a member connecting the ears 20.

The means for cutting or severing the stamps comprises the stationary edge of 10 the slot 22 formed in the plate 23 secured to the frame of the machine and through which the end of the stamp strip is discharged from the curved end of the guide 10. The plate 23 is placed at the edge of 15 the aperture 3 and extends upwardly to provide a stop shoulder 24 to limit the downward movement of the carriage and consequently the feeding movement of the strip. The coöperating cutting or shear member 20 comprises a plate 25 provided at its lower end with a cutting edge 26, which coöperates with the edge of the slot 22 and is thrown into coöperative position by means 25 of the cam members 27 on the plate coming into engagement with the extensions 28 on the plate 23. The plate 25 is slidably and pivotally mounted on the plunger and held in normal position by means of a coiled spring 29 interposed between the plate and 30 plunger. In order to prevent wear of the edge of the knife, the free end of the arms by which it is pivoted to the plunger, are connected to the ends of contractile coiled springs 30, which return the plunger to normal position after operation.

Clamping means are provided for preventing withdrawal of the stamp strip by force applied to its free end. Said clamping means comprises a plate 31 slotted to accommodate the ends of the feeding fingers 13 and having its lower end curved to correspond to the curvature of the guide plate 10 to deflect the stamp strip as it is fed forwardly. At its upper end the plate is 45 bent to form the angular portion 32 where its clamping action occurs when its lower end is moved from the guide 10. The clamping plate is provided with ears 33, in which is mounted a U-shaped member 34 having 50 laterally turned ends extending through slots 34^a in lateral flanges 34^b on the plate, which ends have fixed bearings in the frame of the machine. The clamp is yieldingly held in contact with the guide 10 by means 55 of a coil spring 35 mounted on a T-lug 36 formed on the flange of the plate 31 and having one end secured beneath the lug 37 and the other end provided with an eye 38 wrapped around the adjacent laterally 60 turned end of the U-shaped member 34. As the plate is tilted outwardly at its lower end and exerts clamping pressure at 32 at its upper end, the movement is yieldingly resisted by the springs 35 which press upon 65 it at 36, both ends of the spring being fixed

while the slots 34^a permit rocking movement of the plate about 32 as a fulcrum. In the same way, the springs return the plate and normally hold it yieldingly against the guide.

On the other side of the plunger are provided my improved means for moistening the surface to which the stamp is affixed and associated devices for applying ink to the printing devices 7 already referred to. 70 The inking devices comprise a reservoir or chamber 40 mounted on trunnions 41 and 42 having bearings in blocks 43 and 44 secured to the casing. One of the trunnions 41 has a tapped opening therethrough registering with an opening in the casing, and through which the reservoir may be filled. When in use the opening is closed by means of a shouldered screw 45 which takes in the tapped opening in the trunnion. Normally 80 the reservoir occupies the position shown in Fig. 4 and has an enlarged part 40^a near the top of which is an inwardly extending offset portion 40^b, which lies beneath the types 7 and has an aperture in its upper wall, in 90 which is secured a pad 46 of fibrous material such as felt, sponge or the like, in contact with the types. The ink in the reservoir saturates the pad which applies it to the printing types. Means are provided for 95 swinging the ink reservoir on its trunnions out of the path of the plunger when the latter is actuated to affix a stamp. Said means comprises, in the present instance, a roller or wheel 47 revolvably mounted in 100 the ends of a pair of arms 48 pivotally mounted on a pin 49 secured in the stamp affixing head. The roller 47 normally bears on the top of the reservoir 40 near its outer edge where the top is slightly elevated and 105 is resiliently held in contact therewith by means of a spring 50 coiled about the pin 49 and bearing at one end against the pin on which the roller 47 is mounted and having its other end anchored on a screw 51 110 tapped in the plunger. When the plunger is depressed, the roller rides along the upper surface of the ink reservoir which swings on its pivots from the position shown in Fig. 4, first to that shown in Fig. 6 and 115 finally to that shown in Fig. 5, in which the reservoir has swung completely out of the path of the plunger and its top has moved to a substantially vertical position, while the arms in which the roller is carried have moved from a substantially horizontal position shown in Fig. 4 to a substantially vertical position shown in Fig. 5. When the plunger is returned by the action of its spring, the roller moves back 120 along the side of the reservoir and by the action of its spring 50 swings the reservoir back to its normal horizontal position shown in Fig. 4.

Means are provided for moistening the 130

surface to which the stamp is affixed during the initial movements of the ink reservoir. To this end a water reservoir or chamber 52 is so positioned in the side of the casing that the ink reservoir 40 is pivoted between it and the plunger. The reservoir 52 comprises an upright part 52^a and an enlarged bottom portion 52^b, which extends beneath the ink reservoir into the recess 3 to a point adjacent the path of the plunger and has a bottom portion 53 secured to the base of the casing. Near the base of the part of the reservoir 52^b, the wall is provided with a plurality of orifices or apertures 54, three being shown in the drawings, through which moistening liquid may be expelled from the reservoir upon the surface immediately beneath the plunger, and to which the stamp is applied. For the purpose of filling the reservoir or for replenishing the liquid when exhausted, the outside wall of the casing is provided with a tapped opening leading to the reservoir which may be closed by means of a shouldered screw 55, having a knurled head, by which it may be readily removed. The orifices 54 are comparatively small and means are provided to forcibly eject the water or other moistening liquid therethrough. Said means comprises an ejector 56, the lower or free end of which consists of a plurality of spaced fingers 57, which may be provided with any suitable yieldable material such as rubber or the like. Normally the ejector occupies the position shown in Fig. 4, in which the fingers are yieldingly held in position to close the orifices. The orifices or apertures 54 are of small capillary diameter to prevent the free escape of the liquid therethrough when open, although it will be understood a reduction of pressure will be produced within the reservoir after each ejection of liquid therefrom, and that the atmospheric pressure on the outside will be sufficient to prevent the free escape of the liquid, except when the ejector is being operated. The ejector is pivotally mounted on a rod or pin 58 extending through the reservoir 52 and supported in a pair of inwardly projecting lugs 59 and 59^a. The rod 50 is in the form of a screw, having threads engaging the lug 59. A sleeve 60 is mounted on the pin 58 and extends through ears 61 formed on the ejector and into the lugs 59 and 59^a. The ejector is angular or L-shaped, the angular portion extending in a nearly horizontal plane from a point near its pivotal support when in position to close the orifices 54. Near the extremity of the angular portion, the ejector is provided with an elongated opening 62 adapted to receive a T-head 63 on an actuator 64 for the ejector. The actuator 64 is in the form of a bolt or pin and extends through an opening in the top of the reservoir in which it has an axial sliding movement. At its upper end the actuator is provided with an enlarged head 65 which limits its downward movement. Mounted on the pin 64 adjacent the inner upper wall of the reservoir is a gasket 66, which serves to seal the opening 70 around the bolt. The gasket is resiliently held in position by means of a washer 67 against which one end of a spring 68 bears. The spring is coiled about the bolt 64 and at its other end bears against the angular portion of the ejector and normally holds it in the position shown in Fig. 4, in which the fingers close the apertures 54. The head 65 is bifurcated at its upper end to receive the enlarged horizontal end 70 of a bent arm or lever 71, the other arm 72 of the lever is bent vertically downwardly and at its lower end normally contacts the outer wall of the ink reservoir 40 or a plate 73 secured thereto as shown in Fig. 4. The lever 71 is pivoted 80 to the head by means of a pivot screw and has a recess in its lower face to receive one end of an expansion coil spring 74, the other end of which engages the bottom of the slot in the head 65 and tends to yieldingly hold 90 the lever with its outer shoulder in contact with the bottom of the slot and the arm 72 in engagement with the ink reservoir. The plate 73 is secured to the outer wall of the ink reservoir and projects above said wall, 95 where it is curved outwardly and upwardly to engage the roller 47 and prevent the reservoir from moving past the roller when the plunger is operated. The projecting portion of the plate 73 is slotted or bifurcated and 100 the arm 72 of the actuating lever normally lies within this slot. On its outer wall, the ink reservoir 40 is provided with an actuating lug or projection 75 which normally lies below the end of the arm 71, which it is 105 adapted to engage when the ink reservoir swings to the position shown in Fig. 6, to raise the bolt 64 against the tension of the spring 68 to swing the ejector on its pivot to open the orifices 54. As the plunger is 110 advanced and the parts approach the position shown in Fig. 5, the lug 75 is disengaged from the arm 72 and the spring 68 forces the fingers of the ejector against the openings 54, and in so doing, ejects a quantity 115 of the moistening liquid upon the surface adapted to receive the stamp in advance thereof.

The printing types 7 are provided with shanks 7^a which extend through an elongated slot 76 in a plate 77 secured to the head by means of a pin 78, which extends through the plunger 4 and a pair of ears 79 bent up from the ends of the plate. At one end the slot 76 is enlarged as at 76^a and said 120 enlarged portion has an extension 76^b, as clearly shown in Fig. 11. The types have enlarged heads 7^b, which are inserted through the openings 76^a and engage the rear side of the plate 77, as the types are 125 130

moved along the slot. When the desired types have been arranged in the slot, they are secured in position therein by means of an arm 79 pivoted on a stud or pin 80 secured in the plate 77. The arm 79 has a shoulder or extension 81 adapted to engage the heads 7^b of the types, and a finger-piece 82 for actuating it projects through the slot 76^b. The member 79 is frictionally held in actuated position by its pivot which holds it closely in contact with the plate 77. The head 6 is cut away to form a recess 80^a adjacent to the plate 77 to accommodate the arm 79 and its pivot.

Normally, the parts are in the position shown in Fig. 4. When the plunger is pushed downwardly, the feeding fingers 13 enter the slots in the plate 31 and engage the perforations in the stamp strip to feed it forwardly, until the ears 20 come into contact with the plate 23, and when the stamp at the end of the strip has been advanced through the opening 22, the forward movement of the fingers is then arrested. The severing member 26 has also moved to the position shown in Fig. 5, in which it is adapted to coöperate with the member 23 to shear off the advanced stamp as the plunger advances. During this movement the ink reservoir swings on its trunnions first to the position shown in Fig. 6, in which the inking pad 46 has moved from contact with the types and its outer end away from the arm or lever 71, and the lug 75 has come into contact with the end thereof to swing the ejector fingers 57 away from the orifices 54. As the plunger is advanced to the position shown in Fig. 5, the lug 75 rides past the arm 71, and the spring 68 forces the fingers 40 against the orifices 54 through which a spray of the moistening liquid is ejected upon the surface adapted to receive the stamp about to be severed and forced into contact therewith by the head of the plunger. As the plunger advances, the severed stamp is engaged thereby and pressed into contact with the moistening surface. Simultaneously, the printing type carried by the head impresses the stamp to print thereon.

My invention has been found very useful in cases where it is desirable to cancel the stamp immediately after affixing the same, such as internal revenue, documentary war tax stamps, and the like, where it is desirable to print the date of cancellation on the stamp. It will be understood, however, that it may be used in any place where it is desirable to print upon the stamp simultaneously with the operation of affixing the same. By removing the types from the plunger head, the device can be used as a mere stamp affixer, as the stamps affixed at that time would not be printed. At 82 is shown an indicator which counts the stamps as they are affixed and indicates the number used.

Having described my invention, what I claim and desire to secure by Letters Patent is:

1. In a stamp affixer, the combination of a casing, a plunger adapted to reciprocate therein, means actuated by the plunger for feeding a stamp, means for pressing the stamp on a surface adapted to receive the same, a plurality of printing types on the plunger adapted to print on the stamp, means for inking said types, and devices controlled by said inking means for moistening said surface.

2. In a stamp affixer, the combination of a casing, a plunger adapted to reciprocate therein, means actuated by the plunger for feeding a stamp, means for pressing the stamp on a surface adapted to receive the same, a plurality of printing types on the plunger adapted to print on the stamp, an inking pad movable into and out of the path of the plunger for inking the types, a pivoted member on which the pad is carried, and devices controlled by said pivoted member for moistening said surface.

3. In a stamp affixer, the combination of a casing, a plunger adapted to reciprocate therein, means actuated by the plunger for feeding a stamp, means for pressing the stamp on a surface adapted to receive the same, a plurality of printing types on the plunger adapted to print on the stamp, an inking pad for inking the types, a pivoted member in which said pad is mounted, means on the plunger for moving said pivoted member to swing the pad out of and into the path of the types, and devices controlled by said pivoted member for moistening said surface.

4. In a stamp affixer, the combination with means for pressing a stamp upon the receiving surface and a stamp printing element, of an inking device for the printing element and a moistening device operating in advance of the pressing means, one of which devices is actuated through the medium of the other.

5. In a stamp affixer, the combination with means for pressing a stamp upon the receiving surface and a stamp printing element associated therewith, of a movable inking device for the printing element actuated by the pressing means, and a moistening device actuated by the inking device.

6. In a stamp affixer, the combination with means for pressing a stamp upon the receiving surface and a stamp printing element associated therewith, of a displaceable inking device for the printing element actuated to inoperative position by the pressing means but normally coöoperating with the printing element and a moistening device actuated by the inking device.

7. In a stamp affixer, the combination of a casing, a plunger adapted to reciprocate

therein, means actuated by the plunger for feeding a stamp, means for pressing the stamp on a surface adapted to receive the same, a plurality of printing types on the 5 plunger for printing on the stamp, an inking pad, and an arm on the plunger adapted to swing said pad into and out of contact with the types.

8. In a stamp affixer, the combination of 10 a casing, a plunger adapted to reciprocate therein, means actuated by the plunger for feeding a stamp, means for pressing the stamp on a surface adapted to receive the same, a plurality of printing types on the 15 plunger, an inking pad, an arm pivoted to the plunger, and a roller on the arm adapted to swing the pad into and out of contact with the types.

9. In a stamp affixer, the combination of a 20 casing, a plunger adapted to reciprocate therein, means actuated by the plunger for feeding a stamp, means for pressing the stamp on a surface adapted to receive the same, a plurality of printing types, a swinging reservoir, and an arm on the plunger for swinging the reservoir into and out of the path of the plunger.

10. In a stamp affixer, the combination of a casing, a plunger adapted to reciprocate 30 therein, means actuated by the plunger for feeding a stamp, means for pressing the stamp on a surface adapted to receive the same, a plurality of printing types, a swinging reservoir, an arm pivoted to the plunger, and a roller on the arm adapted to roll on a wall of the reservoir to swing it into and out of the path of the plunger.

11. In a stamp affixer, the combination of a casing, a plunger adapted to reciprocate 40 therein, means actuated by the plunger for feeding a stamp, means for pressing the stamp on a surface adapted to receive the same, a plurality of types on said plunger, a swinging reservoir, an arm pivoted to the plunger, a roller on the arm, and a spring 45 for pressing the roller into contact with a wall of the reservoir to swing the reservoir when the plunger is actuated.

12. In a stamp affixer, the combination of 50 a plunger, means actuated by the plunger for affixing a stamp, a slotted plate on the plunger, and means for securing a plurality of types in said slot to print on the stamp during the affixing operation.

55 13. In a stamp affixer, the combination of a plunger, means actuated by the plunger for affixing a stamp, a slotted plate on the plunger, and an arm for retaining a plurality of types in said plate to print on the stamp during the affixing operation.

14. In a stamp affixer, the combination of a frame, means for feeding and pressing a stamp on a surface adapted to receive the same, printing devices including a swinging 65 reservoir, and means actuated by said reser-

voir for moistening said surface in advance of pressing the stamp into contact therewith.

15. In a stamp affixer, the combination of a frame, means for feeding and pressing a stamp on a surface adapted to receive the same, printing devices including a swinging reservoir, and an ejector actuated by said reservoir for spraying a moistening liquid on said surface in advance of pressing the stamp into contact therewith. 75

16. In a stamp affixer, the combination of a frame, means for feeding and pressing a stamp on a surface adapted to receive the same, printing devices including a swinging reservoir, an ejector for spraying a moistening liquid on said surface in advance of pressing the stamp into contact therewith, and means controlled by said reservoir for actuating said ejector. 80

17. In a stamp affixer, the combination of a frame, means for feeding and pressing a stamp on a surface adapted to receive the same, printing devices including a swinging reservoir, a fixed reservoir, and means controlled by the swinging reservoir for 90 spraying liquid from the fixed reservoir on said surface in advance of pressing the stamp into contact therewith. 85

18. In a stamp affixer, the combination of a frame, means for feeding and pressing a stamp on a surface adapted to receive the same, printing devices including a swinging reservoir, a fixed reservoir, an ejector therein and means controlled by the swinging reservoir for actuating said ejector to 100 spray a moistening liquid on said surface in advance of pressing the stamp into contact therewith. 95

19. In a stamp affixer, the combination of a frame, means for feeding and pressing a stamp on a surface adapted to receive the same, printing devices including a swinging reservoir, a fixed reservoir having an orifice, an ejector in said fixed reservoir, and means controlled by said swinging 110 reservoir for actuating said ejector to spray liquid through said orifice. 105

20. In a stamp affixer, the combination of a frame, means for feeding and pressing a stamp on a surface adapted to receive the same, printing devices including a swinging reservoir, a fixed reservoir having an orifice, an ejector in said fixed reservoir, means on said ejector normally adapted to close said orifice, and means controlled by 115 said swinging reservoir for actuating said ejector to spray liquid through said orifice. 120

21. In a stamp affixer, the combination of a frame, means for feeding and pressing a stamp on a surface adapted to receive the same, printing devices including a swinging reservoir, a fixed reservoir having an orifice, an ejector adapted to swing in said fixed reservoir, means on said ejector for normally closing said orifice, and means con- 125 130

trolled by said swinging reservoir for swinging said ejector to spray liquid through said orifice.

22. In a stamp affixer, the combination of 5 a frame, means for feeding and pressing a stamp on a surface adapted to receive the same, printing devices including a swinging reservoir, a fixed reservoir having an orifice, an ejector adapted to swing in said 10 fixed reservoir and normally adapted to close said orifice, resilient means normally maintaining said ejector in position to close said orifice, and means controlled by said swinging reservoir for actuating said ejector to spray liquid through said orifice.

23. In a stamp affixer, the combination of 20 a plunger, means actuated thereby for feeding and severing a stamp, means on the plunger for pressing a stamp into contact with a surface adapted to receive the same, 25 printing devices actuated by said plunger, and means controlled thereby for spraying liquid on said surface.

24. In a stamp affixer, the combination of 25 a plunger, means actuated thereby for feeding and severing a stamp, means on the plunger for pressing a stamp into contact with a surface adapted to receive the same, printing types on said plunger, devices for 30 inking said types, and means controlled by said inking devices for spraying liquid on said surface.

25. In a stamp affixer, the combination of 35 a plunger, means actuated thereby for feeding and severing a stamp, means on the plunger for pressing a stamp into contact with a surface adapted to receive the same, printing devices actuated by said plunger and comprising a movable ink reservoir, 40 and means controlled by said ink reservoir for spraying liquid on said surface.

26. In a stamp affixer, the combination of 45 a plunger, means actuated thereby for feeding and severing a stamp, means on the plunger for pressing a stamp into contact with a surface adapted to receive the same, printing devices actuated by said plunger and comprising a movable ink reservoir, a projection on said reservoir, and devices 50 adapted to be actuated by said projection for spraying liquid on said surface.

27. In a stamp affixer, the combination of 55 a reservoir for containing a moistening liquid, and having an outlet orifice, an ejector pivoted in said reservoir, a spring normally maintaining said ejector in position to close said orifice, a pivoted member for actuating said ejector, a plunger, and a swinging member controlled by the plunger for operating said pivoted member.

28. In a stamp affixer, the combination of 60 a casing, a reservoir in said casing for containing a moistening liquid and having an outlet orifice, an ejector pivoted in said reservoir, means normally maintaining said

ejector in position to close said orifice, a member pivoted in said casing for controlling said ejector, a plunger, an arm pivoted on said plunger for swinging said member and actuating connections between the latter and the ejector.

29. In a stamp affixer, the combination of 70 a plunger, stamp affixing means actuated thereby, printing types on said plunger, a movable reservoir for inking said types, a fixed reservoir having an aperture, an ejector pivoted in said fixed reservoir, an actuator therefor, and means on said movable reservoir for operating said actuator.

30. In a stamp affixer, the combination of 80 a plunger, printing types on said plunger, stamp affixing means actuated thereby, a movable reservoir for inking said types, a fixed reservoir having an aperture, an ejector pivoted in said fixed reservoir, an actuator therefor, an arm pivoted on said actuator, and means on said movable reservoir 85 adapted to coöperate with said arm to operate said actuator.

31. In a stamp affixer, the combination of 90 a plunger, printing types on said plunger, stamp affixing means actuated thereby, a movable reservoir for inking said types, a fixed reservoir having an aperture, an ejector pivoted in said fixed reservoir, an actuator therefor, an arm pivoted on said actuator, a spring between said arm and said actuator, and a projection on said movable reservoir adapted to coöperate with said arm to operate said actuator when the reservoir moves in one direction and to move the arm from its path without operating the actuator when the reservoir moves in another direction.

32. In a stamp affixer, the combination of 105 a plunger, printing types on said plunger, stamp affixing means actuated thereby, a movable reservoir for inking said types, a fixed reservoir having an aperture, an ejector pivoted in said fixed reservoir, an actuator therefor, a spring normally pressing said ejector over said aperture, an arm pivoted on said actuator, a projection on said movable reservoir adapted to coöperate with said arm to operate said actuator, and an arm pivoted on the plunger for moving said ink reservoir when the plunger is depressed.

33. In a stamp affixer, the combination 110 with a casing, a plunger operating therein to press a stamp upon the receiving surface, a stamp printing element associated with the plunger, stamp feeding mechanism located on one side of the plunger and actuated thereby and a stamp moistening device and an inking device for the printing element located on the opposite side of the plunger and actuated thereby, each of said devices embodying a reservoir adapted to be filled from the exterior of the casing.

WILLIAM F. SCHWEIGER,
